UNITED STATES PATENT OFFICE

GEORGE R. LUM, OF NEW YORK, N. Y., ASSIGNOR TO BELL TELEPHONE LABORATORIES,
INCORPORATED, OF NEW YORK, N. Y., A CORPORATION OF NEW YORK

DESIGN FOR A WALL MOUNTING FOR A HAND TELEPHONE

Application filed August 1, 1931. Serial No. 40,748. Term of patent 14 years.

To all whom it may concern:

Be it known that I, GEORGE R. LUM, a citizen of the United States, residing at New York city, in the county of New York and State of New York, have invented a new, original, and ornamental Design for a Wall Mounting for a Hand Telephone, of which the following is a specification, reference being had to the accompanying drawings, forming a part thereof.

Fig. 1 of the drawings is a front view of a

wall mounting for a hand telephone showing my new design;

Fig. 2 is a plan view; and

Fig. 3 is a side view thereof.

I claim:

The ornamental design for a wall mounting for a hand telephone as shown.

In witness whereof, I have hereunto set my hand this 29th day of July, 1931.

GEORGE R. LUM.
